UNITED STATES PATENT OFFICE.

JOHN O. FJARLI, OF BERWICK, NORTH DAKOTA.

FLY-EXIT FOR WINDOW OR DOOR SCREENS.

1,334,148.

Specification of Letters Patent. Patented Mar. 16, 1920.

Application filed April 7, 1919. Serial No. 288,002.

To all whom it may concern:

Be it known that I, JOHN O. FJARLI, a citizen of the United States, residing at Berwick, in the county of McHenry and State 5 of North Dakota, have invented certain new and useful Improvements in Fly-Exits for Window or Door Screens, of which the following is a specification.

This invention relates to fly exits for 10 window or door screens and has for its object the provision of a comparatively simple and thoroughly efficient device of this character which will permit the ready escape of flies, mosquitos and other insects from the 15 interior of a room while at the same time effectually preventing the return of the insect through the screening material.

The invention further aims to provide a 20 window or door screen having exit openings formed therein and provided at said openings with a supplemental screen or guard for directing the insects to the exit openings.

The invention consists in the novel means 25 for securing the supplemental screen or guard to the main frame whereby said supplemental screen or guard will be supported at an angle or inclination with respect to the screening material of the main frame.

A still further object of the invention is 30 generally to improve this class of devices so as to increase their utility, durability and efficiency.

Figure 1 is a perspective view of a window screen provided with a fly exit embodying the present invention;

Fig. 2 is a longitudinal sectional view taken on the line 2—2 of Fig. 1 and looking in the direction of the arrows;

Fig. 3 is a front elevation of the upper portion of the screen showing the construction of the fly exits;

Fig. 4 is a detail perspective view showing the manner of attaching the supplemental screen or guard to the main supporting frame.

Corresponding and like parts are referred to in the following description and indicated in all the views of the drawings by the same 50 reference characters.

The improved device forming the subject-matter of the present invention may be applied to door or window screens of any desired construction and by way of illustration 55 is shown in connection with a window screen

in which 5 designates the supporting frame including longitudinal side bars, 6 connected by end bars 7 and an intermediate bar 8. Bearing against the outer face of the supporting frame 5 is a continuous strip of 60 wire-screening material 9, said screening material being secured to the side, end and intermediate bars of the frame by suitable retaining strips, indicated at 10. The screening material immediately below the 65 upper bar 7 and intermediate bar 8 is provided with spaced exit openings 11 and the material around said openings is preferably reinforced and strengthened by the provision of suitable eyelets 12 although, if desired, 70 the eyelets 12 may be dispensed with and the openings in the screen formed by punching or spreading the strands of wire to produce said openings.

Arranged at the rear of each set of exit 75 openings 11 is a supplemental screen or guard 13, each guard being preferably formed of a single sheet of wire netting, the upper longitudinal edge of which is secured to the adjacent portion of the frame 80 by the retaining strips 10, while the lower longitudinal edge thereof is extended beyond its ends to form anchoring ears 14 which are slightly twisted so as to overlie the inner face of the frame 5 and are rigidly 85 secured thereto. For this purpose attaching

clips 15 are employed each preferably stamped or otherwise formed from a single strip of metal, the edges of which are bent to produce teeth or spurs 16 adapted to be 90 embedded into the adjacent side bars 6. If desired, a screw or similar fastening device 17 may be passed through each attaching clip 15 and into the frame to assist in securing the ears 14 in position thereon. It 95

will be understood, however, that if desired the clips 15 may be omitted and the ears or extensions 14 on the guard 13 attached directly to the supporting frame. The supplemental screens or guards 13 are disposed 100 at an angle or inclination with respect to the screening material 9 so as to effectually guide flies, mosquitos and other insects through the exit openings 11. It will thus be seen that flies or other insects alighting on the 105 screening material 9 at the interior of the room will crawl upwardly on said screening material and be directed through the exit openings by the guards 13 and inasmuch as the openings 11 are relatively small, liable-

ity of the insects returning to the interior of the room through said openings is reduced to a minimum.

The device is extremely simple in construction and may be readily attached to window and door screens now in use without necessitating any material structural changes therein.

Having thus described the invention, what is claimed as new is:

1. A device of the class described including a frame, screening material secured to the frame and provided with exit openings, and a guard disposed at the rear of the frame and inclined in the direction of the exit openings with the opposite edges of the guard bearing against the inner edges of the frame, said guard being provided with laterally extending ears for attachment to the rear face of the frame, the entire body of the guard with the exception of the ears being disposed within the lines of the frame.

2. A device of the class described including a frame, screening material secured to the frame and provided with exit openings, and a guard leading across the frame at said exit openings and secured along its upper edge thereto, the body of the guard standing oblique to the general plane of the frame and its lower edge extended at its

ends into ears twisted to lie flat upon the inner face of the side bars of the frame, clips fitting over the ears, and fastening devices passing through the clips and ears and into the frame, said guard with the exception of the ears being disposed entirely within the lines of the frame.

3. In a device of the class described, a frame including side bars connected by end and intermediate cross bars, screening material secured to the frame and extending over all of said bars, there being exit openings formed in the screening material immediately below the upper cross bar and intermediate bar, guards independent of the screening material arranged at the rear of the exit openings and inclined in the direction thereof, the upper longitudinal edges of the guards being secured to the adjacent cross bars with the side edges thereof bearing against the adjacent inner edges of the side bars of the frame and with the lower edges thereof extended laterally to form ears for contact with the inner faces of the side bars of said frame, said guards with the exception of the ears being disposed entirely within the lines of the frame.

In testimony whereof I affix my signature.

JOHN O. FJARLI. [L.S.]
